UNITED STATES PATENT OFFICE

CLARENCE T. EVANS, OF WAUWATOSA, WISCONSIN, ASSIGNOR TO CUTLER-HAMMER, INC., OF MILWAUKEE, WISCONSIN, A CORPORATION OF DELAWARE

CIRCUIT CONTROLLING DEVICE

Application filed December 7, 1931. Serial No. 579,450.

This invention relates to improvements in circuit controlling devices, and while not limited thereto is particularly applicable to rheostats of the movable crosshead type.

5 The invention has among its objects to provide a rheostat or similar device with a new and improved type of auxiliary contact mechanism which is adapted to cooperate with the main contacts of the rheostat to minimize arcing therebetween.

Another object of the invention is to provide an auxiliary contact mechanism of the aforementioned character which is of simple, rugged and inexpensive construction and 15 which can be readily removed and reassembled to facilitate inspection or repair thereof.

Another object is to provide an auxiliary contact mechanism of the aforementioned character which is adapted to rotate in a step 20 by step manner to progressively bridge adjacent stationary contacts prior to bridging thereof by the main contacts.

Various other objects and advantages of the invention will hereinafter appear.

25 The accompanying drawing illustrates an embodiment of the invention which will now be described, it being understood that the embodiment illustrated is susceptible of modification without departing from the scope 30 of the appended claims.

In the drawing, Figure 1 illustrates an adaptation of my improved auxiliary contact device to a rheostat of the movable crosshead type.

35 Fig. 2 is an enlarged front elevational view of a portion of the crosshead illustrated in Fig. 1, showing in detail the auxiliary contact mechanism.

Fig. 3 is a view similar to that of Fig. 40 2, showing the auxiliary contact mechanism in another operative position.

Fig. 4 is a top plan view of the same portion of the crosshead illustrated in Figures 2 and 3, and further illustrating the assembled relationship of the auxiliary contact mechanism with respect to the main contacts.

45 Fig. 5 is a side elevational view of the portion of the crosshead illustrated in Figures 2 and 3.

50 Referring to Fig. 1, the same illustrates

a rheostat including a crosshead contactor 1 which is movable over the stationary contacts 2 and 3 mounted upon the insulating panels 4 and 5, respectively. The rheostat may be employed in the control of resistances 55 (not shown) to which the stationary contacts 2 and 3 may be connected, which resistances, it may be assumed, are employed for regulating the speed of a motor. An arrangement of this general character is disclosed in the patent to Reisbach, No. 1,414,709, dated May 2, 1922, and hence detailed description thereof herein is deemed unnecessary. The crosshead 1 is operated by a screw shaft 6 driven by a pilot motor (not 60 shown), and is adapted to be definitely stopped in any one of a number of predetermined positions to effect the desired speed regulation of the aforementioned motor.

The crosshead 1 is provided at each end 70 thereof with a plurality of contact shoes 7 adapted to slidably engage the stationary contacts 2 and 3, and said shoes are arranged side by side upon a cylindrical rod 8, the ends of which bear in the lugs 9 and 10 of the 75 crosshead, as best shown in Figures 4 and 5. The bearing opening in each of the contact shoes 7, which accommodates the rod 8, is preferably in the form of a slot, as shown at 11 in Figure 3, to permit movement horizontally of said shoes to conform to any slight differences in height between individual contacts of the groups 2 and 3, and also to compensate for wear of said shoes. Each 80 of said shoes is spring pressed against the stationary contacts by a pair of compression springs 12 and 13 seated within opposed recesses in the crosshead 1 and in the inner faces of the respective shoes (Fig. 4).

Although the contact shoes 7 are electrically connected to the crosshead 1 as a result of the manner in which the former are mechanically supported by the latter, the contact shoes are preferably additionally provided with flexible leads 14 which are secured to 85 the crosshead by the binding screws 15. As shown in Fig. 1 the crosshead 1 is further provided with the auxiliary contact mechanisms designated in general by the numerals 16 and 17, the construction of which 90

95 100

will be described in detail in connection with the mechanism 17, illustrated in Figures 2, 3, 4 and 5. The mechanism 17 includes a wheel 18 having five bifurcated radial spokes, between the forward ends of the arms of which the roller contacts 19 are rotatably mounted upon pins 20 which penetrate central openings in the respective contacts and aligned openings in the arms of said 10 spokes,—the opposite ends of said pins being enlarged or upset to retain said parts in assembled relation. The wheel 18 is rotatably mounted upon the headed pin 21 which is supported in alined bearing openings in the 15 upper ends of arms 22 and 23 of the lever 24 and is retained therein by a cotter pin 25. The lever 24 is oscillatably mounted upon a pin 26 supported within bearing openings in the lugs 27 and 28 of the frame 29. Said 20 frame is secured to the under side of the crosshead 1 by the screws 30. The roller contacts 19 are biased into engagement with the lateral extensions 39 of the stationary contacts 2 and 3 by a relatively strong compression spring 31 which is confined between the lever 24 and the vertical abutment 32 of frame 29 and is held against lateral displacement by the bosses 33 and 34 formed upon the respective parts. The lever 24 is 25 provided with a depending lug 35 adapted to engage an adjustable stop comprising a set screw 36 and a lock nut 37, to limit outward movement of the wheel 18 for a purpose to be hereinafter described. The set screw 36 has threaded engagement with an 30 opening in the depending lug 38 which is preferably formed integrally with the frame 29.

The auxiliary contact mechanism 16 is 35 like the mechanism 17 aforescribed, except that the frame 29 of mechanism 16 is arranged for mounting on the left-hand side of the cross-head.

The lateral extensions 39 of the stationary 40 contacts 2 and 3 which are adapted to be engaged by the roller contacts 19 are preferably angularly milled or cut away as shown at 39^a. The angular faces 39^a form V-shaped pockets when the contacts are mounted adjacent one another as illustrated in the drawing.

The auxiliary contact mechanisms 16 and 45 17 are adapted to cooperate with the sliding contact shoes 7 in the following manner: As 50 the crosshead 1 moves upwardly, the wheel 18 rotates to insert the roller contacts 19 in the V-shaped pockets formed by the angular faces 39^a to effect bridging of each pair of stationary contacts slightly in advance of 55 bridging thereof by the sliding contact shoes 7, as best illustrated in Fig. 2. The circuit between each two stationary contacts is thus 60 initially completed by the roller contacts 19 and arcing between the contacts 2, 3 and the 65 contact shoes 7 is practically eliminated.

There is a certain amount of arcing between the roller contacts 19 and the angular faces 39^a, but the contact surfaces of each are of such area as to preclude any destructive concentration of the arc. As the wheel 18 rotates to insert one roller contact after another between succeeding V-shaped pockets, it will be seen that each of said roller contacts in turn acts as the fulcrum for said wheel through its corresponding radial spoke, and that as the crosshead 1 continues its upward movement the next succeeding roller contact moves through an arc to approach the V-shaped pocket substantially at a right angle to the face of the lateral extensions 39 of the stationary contacts. This is of advantage since the resultant wear upon the lateral extensions 39 by the roller contacts 19 is almost entirely limited to the areas defined by pockets 39^a. That is to say, the roller contacts 19 move in a direction substantially at a right angle to the face of the extensions 39 to simultaneously engage the opposed angular faces 39^a of each adjacent pair of stationary contacts 2 or 3 regardless of the degree of wear upon said angular faces. Therefore the instant of bridging engagement by the roller contacts 19 with respect to the instant of bridging engagement by the sliding contact shoes 7 remains substantially unchanged regardless of the degree of wear upon the several parts.

During downward movement of the crosshead 1 the foregoing procedure is reversed,—the roller contacts 19 lift out of bridging engagement with the stationary contacts subsequent to disengagement thereof by the contact shoes 7, thus absorbing the arc incident to breaking of the circuit between each pair of stationary contacts.

The stop 36 functions to engage the lug 35 when the crosshead reaches its upper or full speed control position. As shown at 40, in Fig. 4, the stationary contact which provides for full speed control of the aforementioned motor dispenses with the extension 39 which includes the angular faces 39^a. The saving of material is appreciable in consideration of the fact that contact 40 is usually made relatively wide to obviate the necessity for perfect spotting or definite positioning of the crosshead 1. The stop 36 prevents the roller contacts 19 from striking the panels 4 and 5 when the crosshead 1 reaches its full speed control position.

If it becomes necessary at any time to replace the wheel 18 because of worn roller contacts, or for any other reason, removal of said wheel may be effected by merely withdrawing the cotter pin 25 and the bearing pin 21 with which it is associated.

What I claim as new and desire to secure by Letters Patent is:

1. In a circuit controlling device, in combination, a plurality of fixed contacts arranged in spaced parallel relation to each other, a

- contactor movable progressively into and out of bridging engagement with successive pairs of said contacts, and an auxiliary contacting device carried by said contactor and movable therewith, said contacting device comprising a wheel having a plurality of radial spokes, roller contact members rotatable carried adjacent to the outer extremities of said spokes, said wheel being rotatable simultaneously with said contactor, said contacting device including a wheel having a plurality of radial spokes and roller contact members rotatably carried adjacent to the outer extremities of said spokes, said wheel being rotatable during movement of said contactor in one direction to effect insertion of said roller members in a progressive step by step manner into the V-shaped pockets between adjacent stationary contacts prior to bridging engagement thereof by said contactor, said wheel being also rotatable in a reverse direction to effect withdrawal of said roller members from said V-shaped pockets in a progressive step by step manner subsequent to disengagement of said contactor from said stationary contacts respectively. 70
- 10 with movement of said contactor in a given direction to effect insertion of the respective roller contact members successively between the contacts of each pair prior to bridging thereof by said contactor, said wheel being also rotatable during movement of said contactor in the opposite direction to effect withdrawal of the respective roller contact members successively from between the contacts of each pair subsequent to movement of said contactor out of bridging engagement with the latter. 80
- 15 2. In a circuit controlling device, in combination, a plurality of stationary contacts having angular edge portions adapted conjointly to form V-shaped pockets between adjacent contacts, a contactor movable progressively into and out of bridging engagement with said contacts, and an auxiliary contacting device carried by said contactor and movable therewith, said contacting device including a wheel having a plurality of radial spokes and roller contact members rotatably carried adjacent to the outer extremities of said spokes, said wheel being rotatable during movement of said contactor to progressively insert and lift said roller members into and out of engagement with said V-shaped pockets. 90
- 20 3. In a circuit controlling device, in combination, a plurality of stationary contacts having angular edge portions adapted conjointly to form V-shaped pockets between adjacent contacts, a contactor movable progressively into and out of bridging engagement with said contacts, and an auxiliary contacting device carried by said contactor and movable therewith, said contacting device including a wheel having a plurality of radial spokes and roller contact members rotatably carried adjacent to the outer extremities of said spokes, the respective roller contact members being adapted upon rotation of said wheel in one direction to be successively inserted into and lifted out of bridging engagement with successive pairs of fixed contacts in advance of engagement and disengagement of the latter by said contactor, and a spring associated with said lever whereby the roller contact members are biased into engagement with said fixed contacts. 100
- 25 4. In a circuit controlling device, in combination, a plurality of stationary contacts having angular edge portions adapted conjointly to form V-shaped pockets between adjacent contacts, a contactor movable progressively into and out of bridging engagement with said contacts, and an auxiliary contacting device carried by said contactor and movable therewith, said contacting device including a wheel having a plurality of radial spokes and roller contact members rotatably carried adjacent to the outer extremities of said spokes, said wheel being rotatable during movement of said contactor to progressively insert and lift said roller members into and out of engagement with said V-shaped pockets, said wheel being adapted to move said roller members through a path substantially perpendicular to the faces of said stationary contacts. 110
- 30 5. In a circuit controlling device, in combination, a plurality of stationary contacts having angular edge portions adapted conjointly to form V-shaped pockets between adjacent contacts, a contactor movable progressively into and out of bridging engagement with successive pairs of said contacts, an auxiliary contacting device carried by and movable with said contactor, said contacting device including a lever pivotally mounted upon said contactor, a wheel rotatably mounted adjacent to the free end of said lever and having a plurality of radial spokes, roller contact members rotatably carried adjacent to the outer extremities of said spokes, the respective roller contact members being adapted upon rotation of said wheel in one direction to be successively inserted into and lifted out of bridging engagement with successive pairs of fixed contacts in advance of engagement and disengagement of the latter by said contactor, and a spring associated with said lever whereby the roller contact members are biased into engagement with said fixed contacts. 120
- 35 6. In a circuit controlling device, in combination, a plurality of stationary contacts having angular edge portions adapted conjointly to form V-shaped pockets between adjacent contacts, a contactor movable progressively into and out of bridging engagement with successive pairs of said contacts, an auxiliary contacting device carried by and movable with said contactor, said contacting device comprising a frame secured to said contactor, a bifurcated lever pivotally carried by said frame, a wheel rotatably mounted between the arms of said lever adjacent to the free end of the latter, said wheel having a plurality of bifurcated spokes, roller contact members rotatably carried between the arms of said spokes at the outer extremities thereof, the respective roller contact members being adapted upon rotation of said wheel to be successively inserted into and lifted out of bridging engagement with successive pairs of fixed contacts prior to bridging engagement and disengagement thereof respectively by said contactor, and a spring adapted to bias said 130

roller contact members into engagement with said fixed contacts, said spring being confined between the adjacent surfaces of said lever and said frame.

5. 7. In a device of the character described, in combination, a series of fixed contacts arranged in spaced relation to each other, a contactor slidably rectilinearly to effect bridging engagement thereof with and disengagement thereof from each pair of fixed contacts progressively, and an auxiliary contacting device cooperable with said fixed contacts to minimize arcing between the latter and said contactor, said auxiliary contacting device 15 comprising a star-wheel supported by and movable with said contactor, said wheel having roller members located at each of the outer points thereof, said fixed contacts having lateral extensions to be engaged by said roller members respectively in advance of engagement of said contacts by said contactor upon movement of the latter in a given direction.

8. In a device of the character described, in combination, a series of fixed contacts arranged in spaced relation to each other, a contactor slidably rectilinearly to effect bridging engagement thereof with and disengagement thereof from each pair of fixed contacts progressively, and an auxiliary contacting device cooperable with said fixed contacts to minimize arcing between the latter and said contactor, said auxiliary contacting device comprising a star-wheel supported by and movable with said contactor, said wheel having roller members located at each of the outer points thereof, said fixed contacts having lateral extensions to be engaged by said

roller members respectively in advance of engagement of said contacts by said contactor upon movement of the latter in a given direction, and the arrangement being such that said roller members are disengaged from said lateral extensions subsequent to disengagement of said contactor from said fixed contacts upon movement of said contactor in the opposite direction.

9. In a circuit controlling device, in combination, a series of fixed contacts arranged in spaced parallel relation to each other, a contactor slidably movable rectilinearly to effect bridging engagement thereof with and disengagement thereof from successive pairs of fixed contacts progressively, and an auxiliary contacting device comprising a star-wheel supported by and rotatably movable with said contactor, said wheel having roller members located at each of the outer points thereof, said wheel being operable to effect bridging by said roller members successively of each pair of fixed contacts prior to bridging thereof by said contactor and to effect disengagement of said roller members successively from each pair of fixed contacts subsequent to disengagement therefrom of said contactor, depending upon the direction of movement of the latter, said wheel and the fixed contacts being arranged in such relation that the respective contacts of each pair are engaged or disengaged substantially simultaneously by the roller members associated with said wheel.

In witness whereof, I have hereunto subscribed my name.

CLARENCE T. EVANS.
